UNITED STATES PATENT OFFICE.

ANDREW ANDERSON AND VICTOR AXELSON, OF SACRAMENTO, CALIFORNIA.

METHOD OF MAKING MOLDS FOR ORNAMENTAL FLOWERPOTS.

Application filed June 30, 1924. Serial No. 723,223.

To all whom it may concern:

Be it known that we, ANDREW ANDERSON and VICTOR AXELSON, residing at Sacramento, county of Sacramento, State of California, have invented certain new and useful Improvements in Methods of Making Molds for Ornamental Flowerpots; and we do declare the following to be a full, clear, and exact description of the same, reference being had to the accompanying drawings, and to the characters of reference marked thereon, which form a part of this application.

This invention relates to the pottery making or ceramic art, and particularly to a method of making molds for use in turning out flower and similar pots having fanciful designs in relief or embossed on the sides.

Heretofore, in forming molds for pots of this character, it has been necessary to make them in sections, in order to enable them to be withdrawn from the master core on which the ornamental design is first made and which appears in the mold in the reverse order or countersunk. This method is unsatisfactory and expensive for various reasons well known to those who have had occasion to make use of the method and the molds themselves, and pots made from such molds almost invariably show the dividing line between the mold sections in the shape of a thin rib as in metal castings, which at best does not add to the ornamental and finished appearance of the pot.

It is therefore the principal object of our invention to provide a method for making molds for pots of the above named character, such as will enable the mold to be made in one piece, thereby doing away with the sectional form of molding now used.

Our method also enables a number of different ornamental designs being formed with the use of but a single main core member, thus cutting down on the space necessary to carry the cores of a considerable number of different designs.

Our method is very simple and may be quickly and easily carried out, and is much less expensive than the method now in vogue.

These objects we accomplish by means of such structure and relative arrangement of parts as will fully appear by a perusal of the following specification and claims.

In the drawings similar characters of reference indicate corresponding parts in the several views:

Fig. 1 is a side elevation of a core used in connection with the making of our molds.

Fig. 2 is a side view of a detachable ornamental design piece.

Fig. 3 is a side view, partly in section, of the core and surrounding shell assembled to receive the mold material, showing the ornamental pieces on the sides of the core.

Fig. 4 is a sectional view of the assembled parts, with the mold poured.

Fig. 5 is a similar view showing the mold after being withdrawn from the core and with the ornamental pieces still adhered thereto.

Fig. 6 is a similar view, showing the mold after the ornamental pieces have been removed.

Fig. 7 is a side view of an ornamental pot made from our mold.

Referring now more particularly to the characters of reference on the drawings, the numeral 1 denotes the core member used in making the molds, of the same general shape as that of a conventional taper or sloping sided flower pot. A flanged base 2 is formed with the core to support and center a shell 3 in spaced relation to the core, the space between the core and shell determining of course the thickness of the mold to be made.

The design on the surface of the core is what controls the design of the pot 4 ultimately produced. In the present case we prefer to provide the lower portion of the core, which corresponds to the upper portion of the pot, with a permanent plain form of design in relief as at 5, which is of such a nature however as not to interfere with the drawing of the mold from the core.

The main ornamental design features however, of any suitable shape and form, and which are to go on the smooth and sloping sides of the core, are in the form of detachable pieces 6 of flexible rubber or the like, so that they may be disposed in any desired positions about the core. The faces of these pieces which rest against the core are smooth, while their outer faces are formed to properly imitate the flowers or other ornaments they represent.

Before the shell 3 is placed about the core, the pieces 6 are temporarily secured to the core in the proper locations, as shown for instance in Fig. 3, by a suitable adhesive, such as that known in the industry as "clay-slip." The shell is then located in position, and the material 7 for the mold is poured in to fill the space between the shell and core, said material surrounding the pieces 6 on all sides thereof, as shown in Fig. 4.

As soon as the material (usually plaster of Paris) is set, the shell is withdrawn, and the mold 8 is then raised from the core.

In doing this, the pieces 6 are pulled loose from the core, and remain in the mold, as shown in Fig. 5. Said pieces are then peeled out from the recesses 9 formed thereby in the mold, and remain in an undamaged condition to be used again, being of a material which does not tend to permanently adhere to the plaster of the mold. These recesses of course have the imprint of the outer faces of the ornamental pieces, so that when the pot 4 is formed from said mold, the ornamental design shows on the pot as an integral portion thereof and of course, in relief, as at 10.

It will therefore be seen that we have provided a method for the purpose which fulfills the various objects of the invention as set forth hereinbefore.

It is to be understood that detachable ornamental pieces may be applied to the core in place of the permanent design 5, and that said design and that of the detachable pieces may of course be varied as may be desired.

Having thus described our invention what we claim as new and useful and desire to secure by Letters Patent is:

1. A method of making molds for pots and the like having embossed ornaments on their sides consisting in employing a core about which the material forming the mold is poured, and applying to said core before the material is poured, detachable pieces having the desired ornamental configuration.

2. A method of making molds for pots

and the like having embossed ornaments on their sides consisting in employing a core about which the material forming the mold is poured, providing independent pieces having the desired ornamental configuration, and causing said pieces to temporarily adhere to the sides of the core.

3. A method of making molds for pots and the like having embossed ornaments on their sides consisting in employing a smooth faced core about which the material forming the mold is poured, providing independent pieces having the desired ornamental configuration, and temporarily fastening said pieces on said core in the desired location in such a manner that they will be disadhered from the core and withdrawn with the mold when the latter is withdrawn from the core.

4. A method of making molds for pots and the like having embossed ornaments on their sides consisting in employing a smooth faced core about which the material forming the mold is poured, providing independent pieces having the desired ornamental configuration, temporarily fastening said pieces on said core in the desired location in such a manner that they will be withdrawn from the core when the mold is withdrawn and will then adhere to the latter, and then removing said pieces from the recesses formed thereby in the mold.

5. A method of making molds for pots and the like having embossed ornaments on their sides consisting in employing a smooth faced core about which the material forming the mold is poured, providing independent pieces having the desired ornamental configuration, said pieces being of a flexible nature and one face thereof being smooth, and securing the smooth faces of the pieces onto the sides of the core in any desired positions by a temporary adhesive.

In testimony whereof we affix our signatures.

ANDREW ANDERSON.
VICTOR AXELSON.
